UNITED STATES PATENT OFFICE

EMIL K. BLESSING, OF ELKHART, INDIANA

BRASS WIND INSTRUMENT

Application filed May 15, 1928. Serial No. 277,878.

The invention relates to slide devices for wind instruments or brass horns which are employed for tuning the instrument. One object of the invention is to employ but one slide for tuning to B_b and thereafter adjusting for the tone A. A further object is to provide such a construction and fitting of the parts as will avoid undue vibration.

A further object is to eliminate certain structure as will permit the employment of a longer taper mouth pipe or leader to attain more volume, more brilliancy and at the same time secure perfect intonation. A further object is to reduce the number of air pockets within the slide device to a minimum.

In adjusting the instrument for tuning to B_b the player need not remove the mouth piece from his lips, but can tune while playing.

A further object is to eliminate certain braces heretofore used, thus reducing weight and enhancing the appearance of the instrument.

Other objects of the invention will be clear from the following description.

The invention consists in the features and combination and arrangement of parts hereinafter described and particularly pointed out in the claims.

In the drawings:

Figure 1 is a side elevation of a brass horn embodying my invention.

Fig. 2 is a longitudinal sectional view of the slide device.

Fig. 3 is a detail view.

In these drawings 1 indicates the bow forming a part of the slide device which is of single form. That is to say, the usual tuning slide is omitted and but one slide is employed.

This single slide consists of a tube 2 fixed to one end of the bow 1 and a second tube 2^a fixed to the other end of the bow.

The tube 2 is of a length, say, of 5 $\frac{1}{8}$ " over all, with a shoulder 2^b, say 1 $\frac{5}{8}$ " from the inner or rear end, and on the exterior of the tube. This tube 2 is slidably mounted in a main tube 3 forming a part of the fixed main frame of the instrument. This main tube is screw threaded on its interior at 4 and receives a nut 5 which is of sleeve form ex-

teriorly threaded and having its internal diameter the same as the external diameter of the main part of the tube or slide 2. This nut has its screw thread of double form and the interior of the tube 3 is correspondingly threaded to get rapid movement. The nut has an extension 5^a to which a sleeve 6 is attached by soldering or in any other suitable way, said sleeve having an internal diameter to fit the exterior diameter of the main or fixed tube 3 over which said sleeve extends rearwardly from the nut.

The sleeve is knurled at 7 so that it may be readily turned, and when so turned it turns the nut, and as the end of the nut bears against the end 8 of the bow, said bow is moved with its slide tubes 2 and 2^a in relation to the main tubes in which they are mounted and thus the instrument can be accurately tuned for B_b. After this tuning has been effected the adjustment for A pitch can be made by sliding the bow 1 with its slide tubes 2 and 2^a outwardly. The extent of this outward throw of the slide is determined by the shoulder 2^b on the slide tube 2 coming against the inner or rear end of the nut 5 and 5^a.

It will be noted that the portion of the main tube 3 in which the screw thread is formed is of larger diameter than the rest of said main tube for purpose of providing sufficient stock for the screw thread.

The sleeve 6 which forms the finger piece or operating member fits closely upon the smooth cylindrical exterior of this enlarged portion of the main tube and it thus holds the nut against vibration by compensating for any looseness that may develop in the screw thread due to wear.

The double thread is for the purpose of securing a reasonably rapid operation during the tuning action.

With the instrument as above described we have capacity to tune to B_b quickly and to a nicety by the screw thread adjustment with a positive and accurate arresting of a throw-slide to get the tone A on the instrument.

By using but a single slide performing the twofold purpose of tuning to B_b and thereafter throwing to position for the tone 100

A, I can embody in the instrument a longer taper mouth-pipe at 9. The extent of this tapered mouth-pipe is from point 10 to point 11 and by reason of the longer taper the instrument produces tones of great roundness and volume, brilliancy and perfection of intonation. Not only this, but by using only one sliding member instead of two for tuning to B_b and thereafter obtaining the A adjustment, I am enabled to use comparatively long tubes 2 and 2^a and the long bearing thus afforded between these tubes and the main tubes in which they slide prevents binding of the slide and undue strain and wear which ordinarily results from a short slide.

By the use of the nut for tuning to B_b, nicety and ease of adjustment is attained and the possibility of overthrow is avoided which is an objection to a slide adjustment. Further the tuning for B_b can be accomplished while the mouth piece is held at the lips of the player, the tuning of the nut being readily and conveniently accomplished.

The bow of the single slide is provided with a single brace 1^a. No additional bracing is necessary as the comparatively long bearing engagement of the tubes 2, 2^a eliminates the necessity for further bracing. This reduces weight and adds to the appearance of the instrument.

From the above it will be seen that I effect the tuning for B_b by a screw nut adjustment, and this nut when set for said tone B_b acts as a stop for obtaining a setting of the instrument by a throw slide action for the tone A. The nut is arranged on the interior of the main tube and the screw threads are thus concealed, and are protected from damage both by the main tube and by the operating sleeve or finger piece, which encloses the threaded part of the nut when this is adjusted to its outermost position in respect to the main tube. This is a feature of importance because the instrument being formed of brass is susceptible to damage from blows or knocks or rough handling.

As just stated, the outside finger piece or sleeve serves as a cover for the screw threads when the nut is adjusted outwardly and said sleeve thus performs a plurality of functions in that it serves also as a means for holding the nut against vibration, and as a finger piece or operating member. The inner end of the nut serves as the stop against outward movement of the slide while the outer end of the nut serves as a stop for the inward movement of the slide.

I do not limit myself to the proportions of the various parts, or to the association of the novel features of the invention with any particular form of brass instrument as the invention may be used with various kinds of horns besides the trumpet illustrated.

It will be observed that the bow when in

its innermost position is stopped by the nut.

The instrument is so proportioned that when the slide is set all the way in and is arrested by the nut acting as a stop, the pitch of the tone produced is a little higher than B_b i. e. a few more vibrations per second than necessary to produce the tone B_b. By turning the finger piece or sleeve the nut will move outward relative to the threaded end of the main tube, and as it bears upon the bow 1 from the start it will move the bow with the tube sections 2, 2^a immediately and the tone B_b will be produced when the bow is moved out to the proper point. This tuning having been accomplished the tone A can be produced by sliding the U shaped member consisting of the bow 1 and tubes 2, 2^a outwardly, until the shoulder on tube 2 strikes the rear end of the nut which therefore acts as a stop. In other words with my improvement both the tuning for B_b and the quick adjustment for tone A is attained by means of the nut, which acts in the first instance as the operating member for the slide and in the second instance as the stop for the quick action of the slide to the A position. No additional tuning slide is employed.

By reason of using but a single slide, that is to say, omitting the usual tuning slide additionally to the quick change slide, I am enabled to use tubes 2, 2^a of extra length affording long bearings within the main tubes to avoid binding. Further the omission of the usual tuning slide enables me to employ a mouth pipe with a taper of augmented length to give volume and purity of tone.

I have referred to the high pitch as B flat and the low pitch as A, but it will be understood that I mention these tones merely as an example, and that the invention is not limited to instruments thus tuned but is applicable to all other tunings well known in the art.

It will be observed that the position of the shoulder 2^b of tube 2 is such that when the slide is set by turning the nut to the prescribed high pitch position, for example B flat, the arresting of the overthrow movement of the slide by the shoulder 2^b coming against the rear end of the nut will give the prescribed low pitch tone, for example A.

I claim:

1. A brass wind instrument having main fixed tubes, a U shaped slide consisting of tubes slidable in the main tubes and connected by a bow, and a nut having screw threaded engagement with one of the main tubes, said nut acting as a stop for the inward movement of the U shaped slide and as operating means for setting the said slide outward for a given pitch, said nut acting also as a stop for the outward quick adjustment of the slide to another given pitch, the instrument being normally tuned to produce a tone slightly higher than the first mentioned pitch when the slide

is in its innermost position against the nut, substantially as described.

2. A brass wind instrument having main tubes with a single slide mounted therein, said slide having comparatively long tubes working in the main tubes with a nut for adjusting the slide for a prescribed high pitch and for stopping the slide for a prescribed low pitch when slid outwardly in relation to the main tubes, and a mouth pipe with a taper of augmented length, substantially as described.

3. A brass wind instrument having main fixed tubes and a U shaped slide consisting of tubes slidable in the main tubes and connected by a bow, a nut screw threaded into the interior of one of the main tubes to serve as an adjustable stop for the outward movement of the slide, and means for operating the nut consisting of a sleeve rotatively mounted on the plain surfaced outer side of the main tube and connected with the nut, said sleeve concealing and protecting the threads of said nut, substantially as described.

4. A brass wind instrument according to claim 3 in which the rear end of the nut serves as the stop for the outward movement of the slide, substantially as described.

5. A brass wind instrument having a single tuning slide, a screw nut for setting the slide for one prescribed initial tone by rotating the nut and thereby causing the same to move axially for imparting movement to the slide, and without removing the instrument from the lips, said nut serving as a stop when the slide is moved relatively to the nut to thereby arrest the slide in another prescribed tone producing position, substantially as described.

6. A brass wind instrument normally tuned at a higher pitch than a prescribed key tone, and having a slide with a screw nut for moving said slide from normal position to tune the instrument for the said key tone, said nut thereafter acting as a stop for the quick change sliding movement of said slide to another tone position or for its return to the first tone position, said nut forming the sole means of stopping the slide in both its inner and outer positions, substantially as described.

7. In a brass wind instrument the combination of main fixed tubes, a slide having tubes movable in the main tubes, a nut for actuating the slide to a prescribed high pitch position said nut being exteriorly screw threaded into one of the main tubes, one of the tubes of the slide passing through the nut and having a shoulder so disposed that when the slide is moved outwardly through the nut the said shoulder will arrest the slide at the low pitch position, substantially as described.

In testimony whereof I affix my signature.
EMIL K. BLESSING.
